Primary Examiner — Karen S Acker(74) Attorney, Agent, or Firm — Hovey Williams LLP(57) CLAIM

The ornamental design for an inflatable lounger mattress, as shown and described.

DESCRIPTION

FIG. 1 is a front perspective view of an inflatable lounger mattress embodying my design;

FIG. 2 is a rear perspective view thereof;

FIG. 3 is a side elevation view of the inflatable lounger mattress of FIG. 1 with the opposite side elevation being a mirror image thereof;

FIG. 4 is a top view of the inflatable lounger mattress of FIG. 1;

FIG. 5 is a bottom view thereof;

FIG. 6 is a front elevation view thereof; and,

FIG. 7 is a rear elevation view thereof.
